WIRE LOOM WITH WEFT GRAB BARS

Willi Klemm, Neustadt-on-the-Orla, Germany

Application April 27, 1935, Serial No. 18,640
In Germany September 6, 1933

5 Claims. (Cl. 139—130)

This invention relates to looms for the weaving of wire wherein the weft is laid across the warp by means of a pair of reciprocable weft bars.

5 An object of this invention is to provide an improved gripping means for the weft wire whereby either smooth or crimped wire may be laid across the warp, and wherein the weft wire is constantly maintained under sufficient tension to effect operation of a gripping means carried by each weft bar so that the gripping means will securely hold the wire.

Another object of this invention is to provide in combination with the wire gripping means 15 carried by the weft bars an improved means for maintaining a tension on the wire being fed to the weft bars.

A further object of this invention is to provide a means in combination with the weft bars and 20 wire tensioning means, means whereby the loom is automatically stopped in the event of breakage of the wire between the source of supply and the weft bars, or upon failure of the gripping means carried by the weft bars to grab the wire.

25 A still further object of this invention is to provide a single source of supply for a pair of weft bars and to provide a resistance means maintained under automatic tension to prevent loosening of the turns of wire on the supply spool 30 during the withdrawal of the wire from the spool.

With the above and other objects in view, the invention resides in the form, construction and relative arrangement of the parts of a loom construction, as will be hereinafter more fully described, illustrated in the accompanying drawings and subsequently incorporated in the subjoined claims.

In the drawings, wherein **L** have illustrated a practical example of my present improvements, 40 and in which similar reference characters designate corresponding parts throughout the several views,

Figure 1 shows a diagrammatic view from the front of a pair of weft bars constructed according to an embodiment of this invention, together with a wire tensioning means for the weft wire.

Figure 2 is a view similar to Fig. 1, but showing the weft bars in wire transferring position in substantially the center of the warp shed, the latter being omitted for the purpose of better showing the transfer.

Figure 3 is a view similar to Fig. 2, but showing the weft bars at their outermost positions, at which point the weft wire is cut off by sciss- 55 ors at the opposite edges of the warp.

Figure 4 is a longitudinal section, partly in detail of the weft bars showing the bars prior to the transfer of the wire from one bar to another.

Figure 5 is a view similar to Fig. 4 showing the manner of releasing the wire gripping means of 5 one bar during the transfer of the wire.

Figure 6 is a view similar to Fig. 4 showing the position of the bars as the transfer of the wire from one bar to the other is completed.

Figure 7 is a view similar to Fig. 4 showing the 10 weft bars moving away from each other with the wire being drawn through the warp shed.

Figure 8 is a view similar to Fig. 4 showing the manner of releasing the wire in the pulling weft bar at substantially the moment of the cutting 15 off of the wire at the opposite edges of the warp.

Figure 9 is a detail side elevation on a larger scale of the wire tensioning means.

Figure 10 is an enlarged sectional view taken on the line 10—10 of Fig. 4. 20

Figure 11 is an enlarged sectional view taken on the line 11—11 of Fig. 4.

Figure 12 is an enlarged sectional view taken on the line 12—12 of Fig. 4.

Figure 13 is an enlarged sectional view taken 25 on the line 13—13 of Fig. 4.

Figure 14 is a fragmentary diagrammatic view of a modified form of wire tensioning means.

Figure 15 is a diagrammatic view of a further embodiment of wire tensioning means. 30

Figure 16 is a top plan of the woven wire.

Figure 17 is a fragmentary detail side elevation of one of the weft bars.

Figure 18 is a top plan of the bar shown in Fig. 17. 35

Referring to the drawings, and first to Figure 1, the numeral 20 designates a weft bar which is slidably mounted on a guide 21 extending transversely of the frame of the loom (not shown). This weft bar 20 is reciprocated by means of a 40 rock lever 22 connected to a suitable operating means, also not shown and of a conventional character.

The weft bar 20 is a wire carrying bar, and is adapted to carry a weft wire 23 across the warp 45 and within the warp shed. A second weft bar 24 is slidably mounted on the guide 21 in opposed relation to the carrying bar 20 and constitutes a weft draw bar which grabs the wire from the carrying bar 20 and draws the wire across 50 the warp under the action of a rock lever 25, also connected to a suitable lever operating means not shown.

The lower end of the lever 22 is rockably mounted on a stationary part 26 of the frame of 55

the loom, and the lower end of the lever 25 is also rockably mounted on the part 26 of the frame on the side opposite from the connection of the lever 22.

- 5 The wire 23 is initially disposed on a supply spool or pulley 27 which is rotatably supported by a suitable portion of the loom frame, and in the present instance may be mounted on an extension of the part 26 of the frame. The wire 23 is first 10 trained over a tensioning pulley 28 which is yieldingly supported from a spring 29 secured at its upper end to a stationary part of the loom frame. The wire 23 is then drawn downwardly and trained over a second pulley 30 which is rotatably 15 carried by a rock lever 31 extending laterally of the frame part 26. The wire 23 is then brought upwardly and trained over a stationary pulley 32 carried by a pair of arms 33 fixed to the frame of the loom adjacent the end of the guide 21.
- 20 A braking member 34 is mounted on a wire braking lever 35, which is rockably mounted on a frame piece 36. This lever 35 is pivotally secured to the frame piece 36 at a point intermediate the ends thereof, with the braking member 34 at one 25 end of the lever 35, while the opposite end of the lever 35 is attached to one end of a lever tensioning spring 37. The opposite end of the spring 37 is secured to the movable bearing of the tensioning pulley 28.
- 30 A relatively short bell crank arm 38 is fixed relative to the arm 31 and rocks therewith. This arm 38 is connected to a loom stopping bar 39 which is provided with an elongated slot 39a thereby providing a degree of lost motion before 35 the bar 39 is actuated. A spring 40 is connected at one end to the lower end of the frame piece 36 and at the opposite end to the lever 31 so that in the event of undue slack occurring in the wire 23 the lever 31 will be drawn downwardly and the 40 crank arm 38 rocked forwardly to move the stopping bar 39 and thereby stop the loom.
- The weft carrying bar 20 is provided with a guide 41 in which the wire 23 is disposed, and the wire 23 is passed through a wire transferring 45 guide 42 at the forward end of the bar 20, and this guide 42 has a tapering nose 43 through which the wire 23 is adapted to project.
- 50 A wire gripping means, generally designated as 44 is carried by the bar 20 adjacent the forward end thereof, and comprises a toothed gripping member 45 pivoted as at 46 to the bar 20. An arm or lever 47 is fixed relative to the gripper 45 and extends rearwardly thereof. A gripper tensioning lever 48 is pivotally secured as at 49 to the bar 20, and is also pivotally secured at its forward end to the rear end of the arm 47. A tensioning spring 50 is fixed to the lever 48 and has an end thereof disposed in a position for engagement with the wire 23 so as to tension 55 this wire in the guide 41. A threaded tensioning member 51 is carried by the lever 48 and bears against the spring 50 so as to not only tension the gripper 45 against the wire 23 but also to provide a suitable drag on the wire when the bar 20 is moving from beneath the warp shed. This 60 gripper 45 is so mounted in the bar 20 that it will grip the wire 23 as the bar 20 moves forwardly into the shed, but will permit the wire 23 to be drawn forwardly through the bar 20 under the 65 action of the draw bar 24.

The draw bar 24 has a recessed forward end portion 52 shaped to snugly receive the tapered nose 43 when the bars 20 and 24 are in transferring position in the center of the shed. The 70 draw bar 24 is provided with a gripper 53 pivoted 75

as at 54 to the bar 24 adjacent the forward end thereof, and this gripper 53 is reversely positioned with respect to the gripper 45 so that the gripper 53 will firmly hold the wire 23 in the bar 24 as the bar 24 moves outwardly and away from the 5 bar 20. An arm 55 is fixed relative to the gripper 53 and extends rearwardly thereof, the rear end of the arm 55 being pivotally secured to a pressure lever 56, also pivotally secured as at 57 to the bar 24. A pressure spring 58 is secured to the lever 56 and is tensioned by means of a threaded member 59.

As the two weft bars 20 and 24 approach each other in the warp shed the gripper 53 is raised to a released position by means of a draw bar 60 15 which is secured at one end to the gripper 53. A releasing lever 61 is pivoted as at 62 to the bar 24 and is also pivotally connected as at 63 to the draw bar 60. The upper end of the releasing lever 61 has a pivoted portion 61a under 20 tension of a spring 64 which constantly holds the pivoted portion 61a in alignment with the lever 61. This pivoted end 61a is adapted to rock in one direction only so as to swing the lever 61 when this lever 61a strikes a fixed stop 65 carried by the 25 frame of the loom. The lever 61 is under constant tension of a spring 66 carried by the bar 24, and is adapted to move past the stop 65 when the draw bar 24 moves to transferring position, and as this lever 61 is rocked rearwardly by engaging 30 the stop 65, the draw bar 60 will raise the gripper 53 so that the end of the wire 23 projecting forwardly of the nose 42 may freely pass beneath the gripper 53. After the lever 61 passes the stop 65 the spring 66 will swing the lever 61 35 forwardly and coercively swing the gripper 53 downwardly against the end of the wire 23. The swinging of the gripper 53 to gripping position is also facilitated by the spring 58. This release of the gripper 53 is clearly shown in Figure 5 where 40 the end of the wire 23 is shown entering the forward end of the draw bar 24.

In Figure 6 there is shown the meeting of the two weft bars, which is done at the center of the warp shed, and in this position the gripper 53 45 is lowered to grip the end of the wire 23, with the lever 61 swung to its normal position by the spring 66.

Figure 7 shows the weft bars 20 and 24 separating, with the knuckle 61a of the lever 61 passing 50 beneath the stop 65, and in this movement of the weft bars the wire 23 slides through the bar 20 against the tension of the spring 50 and the dragging of the gripping member 45 thereon.

After the weft bars 20 and 24 have moved outwardly beyond the edges of the warp the end of the wire held by the gripper 53 is released by means of a second releasing lever 67 pivoted to the bar 24 rearwardly of the lever 61 and connected to the rear end of the draw bar 60. This 60 releasing lever 67 has a roller 68 on an end thereof which engages with an adjustable cam member 69 secured to a portion of the loom frame. This cam member is adjustable lengthwise of the movement of the draw bar 24 so that the release of the end of the wire 23 may be effected at the proper time dependent upon the width of the warp.

When the wire 23 is released from the draw bar 24 this draw bar 24 may have a slight outward movement sufficient to pull the end of the wire out of the forward end of the bar 24. It will be understood that the releasing lever 67 acts upon the draw bar 60 and the gripper 53 in the same 75

manner as the lever 61 but upon the reverse or outward movement of the weft bar 24.

When the bars 20 and 24 have reached substantially the limit of their outward movement opposed scissors 70 and 71 are actuated by suitable means (not shown) so as to cut off the projecting ends of the wire 23.

Where wire is used which is relatively heavy an efficient form of wire tensioning means should 10 be used, and in Figure 9 there is shown the tensioning means. In this form the wire 23a is taken off of a pulley or spool 27a mounted similarly to the pulley or spool 27, and the wire 23a is then drawn upwardly to a tensioning pulley 15 28a which is yieldingly supported from a spring 29a. The wire 23a is then drawn downwardly and trained over a lower pulley 30a and then upwardly over an upper and fixed pulley 32a. The pulley 30a is mounted on a crank arm 31a 20 connected to a stop rod 39a the same as the crank arm 31. A spring 40a tensions the arm 31a and automatically moves this arm 31a to actuate the stop rod 39a when too much slack appears in the wire 23a, as when the wire is broken 25 or the like.

A brake tensioning lever 35a is mounted on a frame piece 36a and carries a brake shoe 34a engageable with the wire remaining on the spool or pulley 27a. The lever 35a is tensioned by a 30 spring 37a, as in Fig. 1.

In Figs. 17 and 18 there is disclosed the detailed construction of the weft bar 20 which carries the wire from the supply spool to the center of the warp for transfer to the weft bar 24. 35 This weft bar 20 comprises an angular elongated bar 72 having one leg thereof horizontal and the other leg vertical, and at the forward end of this bar 72 there is provided a bearing block or guide member 73 in which the nose or wire 40 guide 42 is slidably. By mounting the guide 42 for sliding movement in the bar 20 the two bars 20 and 24 may have their inner or confronting ends contact with each other during the transferring operation and the shock of the contact 45 will be absorbed by the slidably guide 42. This manner of transferring the wire will permit a relatively short piece of wire to be extended beyond the end of the guide 42 and the inward movement of the guide 42 during the transferring 50 operation will cause the extended end of the wire to be lengthened without bending of the end of the wire. An elongated rod 74 is secured to the inner end of the guide 42, and a spring 75 having one end secured to the rod 74 55 and the other end secured to a pin 76 on the bar 72 constantly urges the guide member 42 outwardly.

In Figure 14 there is shown a further embodiment of this invention wherein a spool 27b of uncrimped wire has the wire strand 23b passed 60 between a pair of crimping members 76 and 77 which are mounted on rock arms 78 and 79 respectively. In this embodiment the wire tensioning means is positioned independently of the frame of the loom, being mounted on any suitable supporting structure. Before the wire 23b enters between the crimping rollers 76 and 77 it passes between staggered rollers or drag members which if desired may be adjusted relative to 65 each other to place the desired drag on the wire.

After the wire 23b passes between the crimping rollers 76 and 77 it is trained over an idling pulley 81 and then passed underneath a tensioning pulley 82 which is mounted on a rock arm or lever 83. The arm 83 is tensioned by means of a 70

spring 84 which constantly urges the pulley 82 downwardly. The wire 23b is then trained over a second idling pulley 85 which is so mounted that the wire 23b is drawn in a straight or horizontal line by the grab bar 20b which is 5 similar to the grab bar 20.

In the construction shown in Fig. 14 the loom is stopped by means of a stop rod 39b having one end secured to a bell crank 86. A lever 87 has an end thereof disposed in the path of the upward 10 movement of the lever 83, and this lever 87 is connected to the bell crank 86 by means of a link 88. A second stop lever 89 has one end thereof rockably connected to a suitable support, and the opposite end thereof is disposed in the 15 path of the downward movement of the lever 83. This lever 89 is connected to a crank 90 by means of a link 91, and the crank 90 may be connected to an arresting mechanism or an alarm mechanism. 20

In Fig. 15 there is shown a still further embodiment of this invention wherein the supply spool 27c is mounted on a standard or support 92 which may be disposed adjacent but independent of the frame of the loom. In this instance the wire 23c may be either initially crimped or may be uncrimped, being here shown as uncrimped and initially passing over an idling pulley 81c and underneath a tensioning pulley 82c carried by a rock lever 93. The rock lever 93 is 25 pivotally mounted as at 94 on the standard or support 92, and the end of the lever 93 opposite from the pulley 82c is formed substantially L-shaped as at 95. The terminal or upper end of the lever portion 95 is provided with a braking 30 member 96 adapted to contact with the periphery of the spool 27c so as to prevent or retard rotation of the pulley or spool 27c when the lever 93 is in its lowermost position. The lever 93 is constantly urged downwardly to tension the wire 23c 35 by means of a spring 97. In this embodiment the stop rod 39c has an end secured to a bell crank 86c, and the bell crank 86c is connected to a stop lever 87c by means of a link 88c, so that when an undue strain is placed upon the wire 23c the 40 lever 93 will be drawn upwardly and will rock the lever 87c and thus effect a stoppage of the 45 loom structure.

The operation of this device is as follows:

The wire 23 is taken from the supply pulley 50 27 and trained over the pulleys 28, 30 and 32, and then threaded into the guide 41 of the weft wire carrying bar 20. The end of the wire is passed through the nose 42 and left projecting slightly beyond the nose 42. It is, of course, assumed that at this time the two weft bars 20 and 24 are at their outermost positions. The weft bars 20 and 24 then move toward each other within the shed of the warp, and just prior to the final inward movement of the weft bars the releasing lever 61 will raise the gripper 53 and permit the projecting end of the wire 23 to pass beneath this gripper. The gripper 45 which acted to hold the wire 23 against movement relative to the bar 20 during the inward movement 65 of this bar 20 will, by reason of its hereinbefore described construction, permit the wire 23 to move forwardly through the bar 20 as the bars move outwardly or away from each other. When the wire 23 is beneath the gripper 53 the lever 70 61 will have passed the stop 65 so that the gripper 53 will be swung downwardly into gripping position by the springs 58 and 66. Just prior to the weft bars 20 and 24 reaching their outermost 75 positions the second releasing member 67 en-

gages the adjustable cam 69 and swings the gripper 53 into released position so that the wire 23 may be completely released from the draw bar 24. At substantially the same moment as the 5 release of the wire 23 by the lever 67, the two scissors 70 and 71 are brought into action and cut off the portions of the wire projecting beyond the warp.

In the above description and the accompanying 10 drawings, I have disclosed embodiments of the invention which have given excellent results in practice. It is, nevertheless, to be understood that insofar as the essential features are concerned, various other arrangements of the 15 mechanical parts of the mechanism might be resorted to to accomplish similar results. Accordingly, it is to be understood that in practice I reserve the privilege of resorting to all such 20 legitimate changes as may be fairly embodied within the spirit and scope of the invention as claimed.

As shown in Figure 14 the wire 23b may be trained over a pulley 98 mounted on a suitable portion of the loom frame, and the wire 23b may 25 be cut in suitable lengths 99 by means of a scissors 100 connected to the operating mechanism of the loom.

I claim:

1. In a loom a pair of reciprocable weft bars, 30 operating means for the bars, rockable weft strand gripping means carried by the bars, the gripping means of one bar being active upon inward movement of said one bar and inactive upon outward movement thereof, the gripping means of 35 the other bar being active upon outward movement of said other bar and inactive upon inward movement thereof, a lever carried by said other bar, means for connecting the lever with the gripping means of said other bar, an abutment disposed in the path of said lever on the inward 40 movement thereof whereby to swing said gripping means to released weft strand receiving position, a second lever connected to the gripping means of said other bar, and a second abutment engageable with said second lever during the 45 outward movement thereof to thereby swing said gripping means of said other bar to released position.

2. Weft laying means comprising a pair of 50 reciprocable elongated members, toothed weft strand gripping means carried by each member, means for pivotally securing the gripping means on the members, a lever carried by one of said members, means for connecting the lever with the gripping means of said one member, an abutment disposed in the path of said lever on the inward 55 movement thereof whereby to swing said gripping means to released weft strand receiving position, a second lever connected to the gripping means of said one member, and a second abutment engageable with said second lever during the outward movement thereof to thereby swing said gripping means of said one member to released position.

3. Weft laying means comprising a pair of reciprocable elongated members, toothed weft strand gripping means carried by each member, means for pivotally securing the gripping means on the members, means for tensioning said gripping means, a lever carried by one of said members, means for connecting the lever with the gripping means of said one member, an abutment disposed in the path of said lever on the inward movement thereof whereby to swing said gripping means to released weft strand receiving position, a second lever connected to the gripping means of said one member, and a second abutment engageable with said second lever during the outward movement thereof to thereby swing said gripping means of said one member to released position.

4. Weft laying means comprising a pair of reciprocable elongated members, toothed weft strand gripping means carried by each member, means for pivotally securing the gripping means on the members, a lever carried by one of said members, means for connecting the lever with the gripping means of said one member, an abutment disposed in the path of said lever on the inward movement thereof whereby to swing said gripping means to released weft strand receiving position, a second lever connected to the gripping means of said one member, and a second abutment engageable with said second lever during the outward movement thereof to thereby swing said gripping means of said one member to released position.

5. Weft laying means comprising a pair of reciprocable weft bars, weft strand gripping means one on each weft bar, said pair of gripping means arranged to permit free movement of the weft strand in one and the same direction and oppose the movement of the weft strand in the opposite direction, a lever for one of said weft bars, means for connecting the lever with the gripping means of said weft bar, an abutment disposed in the path of movement of said lever on the inward movement thereof whereby to swing said gripping means to open weft strand receiving position for receiving the wire strand of the gripping means of the other weft bar, means for moving said first lever beyond said abutment to permit its gripping means to close upon the received weft strand, means for moving said weft bar in the opposite direction for drawing the weft strand therewith, the positioning of the gripping member of the other weft bar permitting the free movement of the strand therethrough, a second lever for the same weft bar having the first lever, a second abutment engageable with said second lever during the outward movement thereof to thereby swing said gripping means of the first lever to weft strand releasing position, and means for tensioning the wire in a direction opposing the gripping means during the movement of said weft bars.

WILLI KLEMM.
